UNITED STATES PATENT OFFICE.

WALLACE WENZEL, OF HOLYOKE, MASSACHUSETTS.

TRUSS.

1,223,751.

Specification of Letters Patent. Patented Apr. 24, 1917.

Application filed June 28, 1916. Serial No. 106,377.

To all whom it may concern:

Be it known that I, WALLACE WENZEL, a citizen of the United States of America, residing at Holyoke, in the county of Hampden and State of Massachusetts, have invented a new and useful Truss, of which the following is a specification.

My invention relates to improvements in abdominal or hernial trusses, and consists of one or more hollow perforated presser members or pads provided with certain peculiar resilient attaching means for the straps with which said pad or pads are secured in place on the body, and further provided with a cover or protector, together with such auxiliary and subsidiary parts and members as may be needed to render the truss complete and serviceable, all as hereinafter set forth.

One object of my invention is to produce a comparatively simple and inexpensive truss with which a steady pressure can be maintained over the hernial spot or spots without liability of displacement, on the part of the pad or pads, due to any action or movement of the body or legs of the person wearing the same.

I prefer to employ a metallic pad that is ventilated by means of perforations, not only in the front side, but also in the back side, in order that such pad shall be cool and comfortable, due to the admission of air through the perforations to the interior of said pad, and the consequent circulation, to some extent at least, therethrough. The presence of the perforations in the back side of the pad may cause an irritation of the skin, and sometimes hairs on the body catch in the perforated parts, and in the pad connections as well, and are pulled, wherefore a further object of the invention is to prevent such undesirable results, which I do by introducing a protector between said pad and its connections and the body. The aforesaid protector prevents the metal of the pad and connections from coming into direct contact with the flesh, without, however, decreasing the efficiency of the pad. The use of the protector also enlarges the choice of metals which I may employ in the construction of the pad and connections.

Still another object is to provide convenient, secure, and efficient means wherewith or whereby the pad and straps can be readily connected and disconnected.

Other objects and advantages will appear in the course of the following description.

I attain the objects and secure the advantages of my invention by the means illustrated in the accompanying drawings, in which—

Figure 1 is a perspective view of a double truss which embodies a practical form of my invention, the left-hand protector being closed and secured in place on its pad, while the right-hand protector is unfastened and laid open; Fig. 2, a sectional detail of one of the strap connections, taken on lines 2—2, looking in the direction of the associated arrow, in Fig. 1; Fig. 3, a vertical section through one of the pads, on lines 3—3, looking in the direction of the associated arrow, Fig. 1; Fig. 4, an inside elevation of the front section of one of said pads, showing the interior members; Fig. 5, a detail showing a modified form of post and means of connection between post and helical spring; and, Fig. 6, a detail showing a means of connection between helical spring and pad casing.

The first view is on a smaller scale than the other views.

Similar numerals refer to similar parts throughout the several views.

Although I have shown and will describe a double truss, that is, a truss which includes two pads, two perineal straps, and a connection between said pads, it is obvious that, by omitting one of said pads and one of said straps and said connections, the truss becomes a single truss.

The truss comprises, with two pads 1 and their accessories which will presently be described, the necessary straps which include a body belt 4, two perineal straps 5, and a short connection 6. The belt 4, the straps 5, and the connection 6 may be made of any suitable material and in any suitable manner, but I prefer to employ a double or looped strap for each, or in any event for said belt and said straps 5, employing clasps 7—7 of special construction with which to secure the free ends of the belt and of the perineal straps.

Each clasp 7 comprises two longitudinal slots 8 and two transverse slots 9. The clasps 7 are mounted for adjustment on the belt 4 which passes through the slots 8. The terminals, as 10 and 11, of the belt 4 are passed through the slots 8 in one of the

clasps 7, the left-hand clasp in this case, and after proper adjustment such terminals are left and they are held in place by reason of the frictional resistance which exists between the contiguous parts. The free ends 5 of the straps 5 are adjustably secured to the clasps 7 by passing the inner or front terminal laps (12) up and through the bottom slots 9, and up again and through the upper slots 9, leaving the extreme end portions 10 hanging, as at 13, and by passing the outer or rear terminal laps (14) up and through said upper slots 9, on top of the laps 12, and down in front of said laps 12 and through 15 said bottom slots under said laps 12, leaving the extreme end portions hanging, as at 15. Thus adjustable connections are formed for the perineal straps 5 relative to the belt 4, such connections being of the friction variety similar to those of the belt terminals, 20 so that the rear looped terminals of said straps can be located, secured, and supported at the most advantageous points.

The clasps 7 are especially adapted for 25 my purpose because they are flat, and even though tongueless afford the necessary security, owing to the frictional resistance that exists when said clasps are in place on the belt 4 and the straps 5 are attached 30 to the clasps. Being without tongues the clasps 7 can very readily be adjusted on the belt and the perineal straps in said clasps. or said belt and straps through said clasps.

At each looped terminal of the belt 4 and 35 of the connection 6 is a fastener 16, and at the front looped terminal of each strap 5 is a fastener 17. The fasteners 16 have slots 18 which open out of recesses 19 therein. The fasteners 16 might be substituted for 40 the fasteners 17, and vice versa, for that matter.

Each pad 1 is hollow and has perforations 20 in both the back and front sides. Said pad is usually made of metal, and constructed 45 in two parts or sections which are screw-threaded at their edges and united by being screwed together, as represented at 21 in Fig. 3.

Covers, wrappers, or protectors 22 are 50 provided for the pads 1. The protectors 22 are made out of some suitable fabric, are of a size and shape which enables them, not only to form backings for the pads 1 and the fasteners 16 and 17, but to be folded 55 over the edges of said pads and around said fasteners and the looped portions of the belt 4, connections 6, and straps 5, so that such parts can not come into direct contact with the flesh. The protectors 22 may be 60 sewed into place on the pads 1 and their connections, or otherwise secured, either permanently or temporarily, snap-fasteners 23 of ordinary construction being here shown. The snap-fasteners 23 enable the 65 protectors 22 to be easily and quickly re-

moved and replaced, they being removed when soiled and it is necessary either to cleanse them or throw away the old and substitute new protectors.

Each pad 1 has in the front side thereof 70 three radial slots 24, and is equipped with the same number of radially-movable posts 25. Each post 25 extends forward through and beyond and operates in the slots 24. The fasteners 17 are permanently attached 75 at their upper ends to the outer ends of the lowermost posts 25. The other posts 25 have at their outer ends heads, such as are indicated at 26, or each of such posts may assume the form of a hook at the outer end, 80 as represented at 27 in Fig. 5. In the event fasteners 16 be substituted for the fasteners 17, all of the posts 25 will have the heads 26, or equivalent members, which are adapted to engage and assist in retaining said 85 fasteners 15 in place. The inner portion of each post 25 is securely attached to the outer terminal of a helical spring 28, as by means of a nut 29 tapped onto said post and binding said spring terminal between said 90 nut and a shoulder 30 on said post, as best shown in Fig. 5. The inner part of each post is turned down or reduced in diameter to form the shoulder 30, and the outer terminal of the attached spring 28 encircles 95 such reduced part of said post, between said shoulder and the nut 29 on the inner end of the post.

The helical spring 28 for each post 25 has its inner end firmly attached to the 100 front of the pad 1 in which such spring is located. As a means of attachment, for each spring 28, I may provide said spring at the inner end with an enlargement 31 which is rectangular in cross-section, and 105 has a reduced part 32 that fits into a slot 33 in the front of the pad 1 to which said enlargement is attached, and secure the latter to said pad by means of a bolt 34 and a nut 35—see Fig. 6. Each bolt 34 passes through a longitudinal opening in one of the members 31, with the head of such bolt bearing against the outside of the front of the pad 1 which carries said parts, and the nut 35, which is on the inner end of said bolt, forces the shouldered part of said member 31 against the inside of said front of the pad, and draws said head tightly against said outside of said front. This is 110 made possible because the length of the reduced part 32 of each enlargement 31 is less than the thickness of a pad front. It will now be seen that the enlargements 31, with their springs 28, are securely and rigidly 115 affixed to the front sides of the pads 1.

Auxiliary springs 36 of the spiral type are also provided in the pads 1, for the purpose of augmenting the force of the helical springs 28. The springs 36 are arranged 120 in such a manner, between the ends of the 130

5 springs 28 to which the posts 25 are attached and adjacent parts of the side walls of the pads, that said springs 36 exert an inward pressure on said ends of said springs 28 and said posts. The outer ends of the 10 springs 36 are held in place by lugs 37 which project inwardly from the side walls of the pads into said springs, and the inner ends of said springs are held in place by lugs 38 which project into said springs from the ends of the springs 28 that embrace the posts 25.

15 The arrangement of the springs 28 and 36 is such that said springs normally retain the posts 25 at the inner ends of the slots 24. The slots 24 both limit the movement of and guide the posts 25. Said posts afford points of attachment for the slotted fasteners 16, as well as for the fasteners 17, said 20 fasteners 16 being slipped on and off over the heads 26 (or hooks, as 27) which latter are receivable in the recesses 19, in the manner customary with fasteners of this type.

25 The slotted fasteners 16 form pivotal connections with their posts 25 of such a nature that the belt 4 and the connection 6 can move freely, relative to the attached pads, without disturbing the latter or turning or twisting the same on the hernial 30 spots. Pivotal movement of the fasteners 17 might be obtained, if desired, by leaving the nuts 29 slightly loose.

35 The springs 28 and 36 afford the required amount of flexibility for the body straps, yielding by contraction when such straps are drawn away from the pads, and expanding to take up slack, thus keeping said straps taut at all times, so that the 40 straps need not be made of elastic material, although elastic material may be employed, if desired.

45 The truss is first applied by encircling the body with the belt 4, bringing the perineal straps 5, with the pads 1 attached thereto, up between the legs, and attaching the fasteners 16, including those of the connection 6 in the event the latter be not already in place, to said pads. At this time and as a part of the adjusting and fastening operations, the pads 1 are located directly over the hernial spots. The slotted 50 fasteners 16 are slipped into place, over the post heads 26, and then moved outwardly to locate the upper posts 25 in the outer ends 55 of the slots 18, such outer ends being between the front of the pads and said heads. The first time that the truss is applied, and at other times if necessary, the belt 4 and the perineal straps 5 are adjusted, as may 60 be required to locate the pads 1 in proper position and arrange them so that they fit securely but comfortably the body of the wearer, by drawing the straps comprising said belt and perineal straps through the 65 clasps 7 to lengthen or shorten them as

needed. The precise manner of adjusting the belt 4 and the straps 5 will be understood from the drawings and the explanation hereinbefore given.

To facilitate the removal of the truss 70 from the body, one or more of the fasteners 16 may be detached or disconnected, which can be done without opening either of the protectors 22, provided the latter do not fit too tightly the pads and connections. 75 And the same fastener or fasteners must, of course, be again connected when the truss is replaced on the body.

80 The fasteners 17 are permanently attached to their posts 25, because it is not necessary to disconnect the straps 5 from the pads 1, when provision is made for disconnecting the belt 4 from said pads, although it would be a simple matter to render said straps disconnectible, as previously ex- 85 plained.

These pads being thoroughly ventilated are sanitary and comfortable.

85 The connection 6 is really, of course, one of the body straps or a part of the belt 90 element, being in fact an auxiliary, detachable or detachable portion of the belt 4.

90 The shape, size, arrangement, and construction of the truss elements may be modified or changed, even beyond that I have 95 herein specifically shown and explained, without departing from the spirit of my invention or exceeding the scope of my claims.

95 What I claim as my invention, and desire to secure by Letters Patent, is— 100

100 1. The combination, in a truss, with a belt and a perineal strap provided with fasteners, of a hollow slotted pad, helical springs in said pad, means to secure the inner ends of said springs to said pad and prevent 105 such ends from turning on their axes, posts for said fasteners, and means to attach said posts at their inner terminals to the free ends of said springs, said posts extending through and operating in the slots in said 110 pad.

110 2. The combination, in a truss, of a belt and a perineal strap provided with fasteners, a hollow slotted pad, helical springs in said pad and having their inner ends secured thereto, and fastener-engaging members attached at their inner terminals to the free ends of said springs, and extending through and operating in the slots in said 115 pad, the fastener connected with said perineal strap being permanently attached to one of said fastener-engaging members, and the fasteners connected with said belt being attachable to and detachable from the others of said members. 120

125 3. The combination, with a hollow slotted truss pad, of helical springs in said pad, the inner ends of said springs being enlarged and seated in the slots provided for them in a wall of said pad, bolts passing through 130

said wall and the enlarged parts of said springs, nuts on said bolts to bind said enlarged parts to said wall, the latter and said enlarged parts being clamped between the heads of said bolts and said nuts, and posts carried at the outer ends of said springs.

4. The combination, with a hollow slotted truss pad, of helical springs in said pad and having their inner ends secured thereto, 10 shouldered posts carried at the free terminals of said springs, and nuts on said posts to confine the parts of said springs, that engage said posts, between the shoulders on the posts and said nuts, to secure said posts 15 to said springs, said posts being guided and having their movement limited by the edges of the slots in said pad.

5. The combination, with a hollow slotted truss pad, of helical springs in said pad, the 20 inner ends of said springs being enlarged and seated in the slots provided for them in said pad, bolts and nuts arranged to bind the enlarged parts to said pad, shouldered posts carried at the outer ends of said posts 25 carried at the outer ends of said springs, and nuts on said posts to secure the latter to said springs, said posts operating in other slots provided for them in said pad.

6. The combination, in a truss, with a belt and a perineal strap provided with fasteners, of a hollow pad, helical springs in said pad and having their inner ends secured thereto, fastener-engaging members attached to the outer ends of said springs, and auxiliary springs arranged in said pad to 30 bear against said outer ends of said helical springs and assist in retaining normally 35 said fastener-engaging members in normal position.

7. The combination, in a truss, with a belt 40 and a perineal strap provided with fasteners, of a hollow slotted pad, helical springs in said pad and having their inner ends secured thereto, fastener-engaging members attached at their inner terminals to the free 45 ends of said springs, and extending through and operating in the slots in said pad, and auxiliary springs arranged in said pad to bear against said free ends of said helical springs and assist in retaining normally 50 said fastener-engaging members at the inner ends of said slots.

WALLACE WENZEL.
